UNITED STATES PATENT OFFICE.

WILLIAM RICHARD AND OSCAR M. HOLCOMB, OF BLOOMVILLE, OHIO; SAID
WILLIAM RICHARD ASSIGNOR TO JOHN D. WILSEY, OF SAME PLACE.

SHEARS.

SPECIFICATION forming part of Letters Patent No. 330,738, dated November 17, 1885.

Application filed May 16, 1885. Serial No. 165,747. (No model.)

To all whom it may concern:

Be it known that we, WILLIAM RICHARD and OSCAR M. HOLCOMB, both residents of Bloomville, in the county of Seneca and State 5 of Ohio, have invented certain new and useful Improvements in Shears; and we do hereby declare that the following is a full, clear, and exact description of the invention, which will enable others skilled in the art to which it 10 appertains to make and use the same, reference being had to the accompanying drawings, which form a part of this specification.

Our invention has relation to shears; and it consists in certain new and useful improvements upon the principles embodied in the 15 pruning-shears for which William Richard has filed an application for Letters Patent in the United States Patent Office, Serial No. 161,450, as will be hereinafter fully described, and particularly pointed out in the claim.

Referring to the annexed drawings, Figure 1 is a side view of our improved shears, showing the same open. Fig. 2 is a perspective view taken from the opposite side to that 25 shown in Fig. 1.

The same letters of reference indicate corresponding parts in both the figures.

Referring to the several parts by letter, A represents the stationary blade or main portion 30 of the shears, which is provided with the recess A', which is circular in shape, with the exception that at its outer side it is open for about one-fourth of its circumference, the depth of the said recess being about three-fourths of the thickness of the main blade at 35 the point where the said recess is formed.

B represents the movable handle or operating-lever, which is provided with the nearly-circular projection B', adapted to fit and work 40 in the recess A', the said projection being of such a thickness that when placed in its operative position in the said recess its outer side or face will be flush with that face of the main blade with which it is contiguous. The 45 operating-lever B is also provided with the outer projection, B², to which the upper end of the slotted movable auxiliary blade C, with or without a washer on, is pivotally connected.

C represents the sliding auxiliary blade

having the pivot-slot C', with or without a washer, and adapted to be pivotally connected at its upper end, at a, to the outer extension of the lever-blade, being further provided with the semicircular ear or projection C², which, when the several parts of the shears 50 are connected together in their operative positions, extends over the circular projection B' of the operating-lever and the recess in which it works, a pin or pivot, A², passing through the pivot-slot C' and into the main blade A, 55 as shown, thereby forming the fulcrum on which the movable blade C turns. It will be seen that when the circular inner projection, B', of the operating-lever has been placed in the nearly-circular recess A' it is impossible 60 for it to work out of the same sidewise, as the side opening of the said recess is less than the diameter of the said projection, that portion of the main blade extending over the nearly-circular recess preventing the escape of the 65 lever-projection B' in that direction, while the curved ear or projection C² of the sliding blade C, which, as before stated, extends over the projection B', serves to prevent the same from 70 working out of the recess, thereby dispensing 75 with the use of pivots or other similar fastening devices for the connection of the operating-lever with the stationary or main handle.

From the foregoing description, taken in connection with the accompanying drawings, 80 the construction of our improved shears will be readily understood without requiring further explanation.

It will be seen that by constructing our improved shears in the manner described we 85 obtain an immense increase in leverage power, the blade being also given a drawing cut, which is an additional advantage in cutting any heavy fabric or material. By this construction we also simplify the construction of 90 the shears and decrease the expense of their manufacture as compared with the shears for which William Richard has filed an application for Letters Patent, Serial No. 161,450.

Having thus described our invention, we 95 claim and desire to secure by Letters Patent of the United States—

The combination of the main blade having

the circular recess open at one side for about one-fourth of its circumference, the operating-lever having the nearly-circular lower projection adapted to fit and turn within the said recess and provided with the upper projection, and the auxiliary sliding blade having the pivot-slot and the inner ear or projection and pivotally connected at its upper end above the said slot to the upper projection of the operating-lever, all constructed and arranged to

operate in the manner and for the purposes shown and set forth.

In testimony that we claim the foregoing as our own we have hereunto affixed our signatures in presence of two witnesses.

WILLIAM RICHARD.
OSCAR M. HOLCOMB.
